UNITED STATES PATENT OFFICE.

SAMUEL J. SEELY, OF BROOKLYN, NEW YORK.

IMPROVED MODE OF STRENGTHENING AND IMPROVING SHEET-IRON BUILDINGS.

Specification forming part of Letters Patent No. 41,787, dated March 1, 1864.

To all whom it may concern:

Be it known that I, SAMUEL J. SEELY, of Brooklyn, in the State of New York, have invented a new and useful Process for Strengthening and Improving the Walls or Floors of Sheet-Iron Buildings; and I do hereby declare that the following is a full and exact description thereof.

I have been for a long while engaged in the building of sheet-iron houses. These are usually made with what may be termed an "inner" and an "outer" skin of sheet-iron of suitable thickness, either plain or corrugated, having a space between the skins of from about four to six inches. In order to render the building warmer, it is customary to fill the intermediate space with sawdust, brick, earth, or ashes. It will be seen that the sawdust from its lack of cohesion can contribute but very little, if any, to the strength of the structure, and that the two skins must be of considerable thickness in order to possess the requisite strength to withstand external accidents or blows which might indent or puncture the skin and permit the sawdust to escape; and, again, since the outsides of both skins are painted, condensation and oxidation take place upon the inner surfaces and greatly injure the building. By my process all of these difficulties are avoided.

My process consists simply in making a cheap and hard cement (composed of sand and Rosendale cement or other suitable materials) of a barely fluid consistency, and then pouring it between the two metallic skins until the whole space and all the crevices between them are filled. When the cement becomes hard the walls or floors will be found to be as rigid and strong as if made of stone. There can be no indentations made in the sheets, and I can make use of much thinner metal than I could if the space had been filled with sawdust. There will be perfect freedom from oxidation and from vermin.

I may apply this process to buildings made with plain sheets of metal, but think that the best results are obtained from corrugated or ridged sheets of metal.

Having thus described my invention, what I claim as new, and desire to secure by Letters Patent, is—

The process herein described of strengthening and otherwise improving the walls or floors of sheet-metal buildings.

SAML. J. SEELY.
